CLAIM

The ornamental design for a holder for charging mobile phone, as shown and described.

DESCRIPTION

FIG. 1 is a front/left-side/top perspective view of a holder for charging mobile phone showing our new design;

FIG. 2 is a front-side elevational view thereof;

FIG. 3 is a rear-side elevational view thereof;

FIG. 4 is a left-side elevational view thereof;

FIG. 5 is a right-side elevational view thereof;

FIG. 6 is a top-side elevational view thereof; and,

FIG. 7 is a bottom-side elevational view thereof.

The broken line showing is included for the purpose of illustrating boundaries of the claimed design and environmental structure, and forms no part of the claimed design.
